DESIGN FOR AN AIR COMPRESSOR

Roland A. Manning, Milwaukee, Wis., assignor to
The Electric Sprayit Co., a corporation of Del-
aware

Application September 2, 1938, Serial No. 79,718

Term of patent 14 years

To all whom it may concern:

Be it known that I, Roland A. Manning, a citizen of the United States, residing at Milwaukee, in the county of Milwaukee and State of Wisconsin, have invented a new, original, and ornamental Design for an Air Compressor, of which the following is a specification, reference being had to the accompanying drawings, forming part thereof.

Fig. 1 is a front elevational view of an air compressor showing my new design;

Fig. 2 is a top plan view thereof;
Fig. 3 is a rear elevational; and
Fig. 4 is an end elevational view thereof taken from the right of Fig. 3.

I claim:

The ornamental design for an air compressor, substantially as shown.

ROLAND A. MANNING.
